Application March 10, 1943, Serial No. 478,670

5 Claims.

(Cl. 248—19)

This invention relates to improvements in foundations and more particularly to foundations which in use will be subjected to heavy stresses and strains such as are encountered, for example, in the use of certain types of machinery, buildings, etc. The invention is of especial advantage in connection with drop or power hammers whose foundations, commonly called anvil blocks, are usually made in unitary cast steel pieces of great size. Cast steel is not entirely satisfactory for this purpose because it is a relatively hard and brittle metal and consequently often cracks and breaks down under the heavy blows to which it is subjected in such use. Furthermore, the production of such a block which contains an immense mass of metal, is difficult and slow due to the fact that it is necessary to allow from six to eight weeks for the block to cool after the metal has been poured and during such period great care must be exercised to assure a proper formation of the ultimate block. Even so, there is no ready way of ascertaining and controlling what takes place in the interior of such a large mass of material during the cooling period and it is not an uncommon occurrence for such blocks to fail because of hidden structural weaknesses, which failure is hastened because of the inherent inability of the cast steel to successfully absorb the shocks of the hammer blows. Another disadvantage of such foundations is that their great weight renders them difficult to handle and install.

The principal object of this invention is to provide a simple and durable foundation construction which will not possess the aforementioned disadvantages, but which will successfully withstand heavy stresses or strains for long periods of time without failure, will be relatively easy to produce and can be handled and installed without any great trouble.

Other objects of the invention, as well as the advantages and novel features of construction thereof, will become apparent after a perusal of the following description, read in connection with the accompanying drawings in which Fig. 1 is an elevational view of a portion of a hammer provided with an anvil block embodying the invention; Fig. 2 is a sectional plan view taken along the line 2—2 of Fig. 1; Fig. 3 is a side elevational view of the parts shown in Fig. 1; Fig. 4 is a detailed view in vertical section of a portion of a foundation to illustrate a modified form of the invention and Fig. 5 is a detailed partial view illustrating a further embodiment of the invention.

In Figs. 1 to 3 of the drawings, the reference numeral 10 indicates the concrete main base of a

large sized steam hammer of usual type. Mounted on the base 10 is a sub base 11 which may be made in accordance with the teachings of this invention or from a cast steel block which may be of any suitable thickness, such as, for example, about two and one-half feet thick, and which is secured to the base 10 in part by a plurality of vertically disposed anchor bolts 12. The sub base 11 forms a support for the foundation of the hammer or anvil block which is indicated generally by the reference numeral 13. The block or foundation 13 is provided at its upper end with a dove-tailed seat which extends centrally between the ends of the block and into which is fitted the dove-tailed sow block 14 bearing the die 15. The super-structure 16 of the hammer is footed on the upper end of the anvil block 13 on either side of the centrally positioned sow block 14. The footings of the super-structure are secured to the anvil block 13 by a number of vertically disposed bolts 17 which extend down through the block to a point adjacent to its bottom end and by a number of bolts 18 which extend through the upper portion only of the anvil block 13, as can be seen more clearly in Fig. 1 of the drawings.

The anvil block 13 is a laminated structure in that it is composed of a plurality of horizontally disposed plates laid one upon the other and having the same or different thicknesses as may be deemed advisable. Generally speaking, however, the plates should be as heavy as it is possible to obtain for the heavier types of machines but may vary in sizes and weights according to their applications. In the anvil illustrated in the drawings, there is included in the laminated structure a top plate 19, groups of intermediate plates indicated by the reference numerals 20 and 21, and a bottom plate 22. The opposed surfaces of the plates are corrugated, the elongated ridges of each of such surfaces being seated in the troughs of an adjacent surface, as is shown more clearly in Fig. 1 of the drawings, to provide an interlocking connection between the plates such as to prevent relative movement between the plates in one direction. The plates constituting the anvil block 13 are maintained against movement or slippage in directions longitudinally of the corrugations by means of vertical bolts of different lengths and positioned at different places in the block. Thus, a number of vertical bolts 23 are provided to prevent such slippage as between the six lowermost plates, such bolts 23 being inverted and the head thereof seated in recesses 24 provided in the top surface of the bottom plate 22, while the shanks of such bolts extend upwardly through

aligned openings provided in the five plates overlying the bottom plate. The recesses 24 are made sufficiently deep so that the entire heads of the bolts are contained in such recesses and are below the top surface of the bottom plate 22. The shanks of the bolts have a length less than the combined thickness of the plates through which they extend so that the upper ends of the shanks terminate short of the bottom surface of the next overlying plate which is not provided with an aperture aligned with the said apertures of the underlying plate. The bolts 23 are also preferably of such outside diameter that while they fit relatively snugly in the apertures of the plates, they do not form a tight fit in such apertures. Also the bolts 23 may be bushed and lubricated to slide with relation to the plates. In a similar manner the bolts 25 prevent slippage longitudinally of the corrugations of the top seven plates of the anvil block 13, such bolts 25 having their heads positioned in recesses 26 provided in the upper surface of the second plate from the bottom in the group designated 20 and sufficiently deep so that such heads are positioned below such surface. The shanks of bolts 25 are of such length that they terminate just short of the under-surface of the sow block 14. Further, the bolts 25 are so arranged that they lock the upper plates of the anvil block 13 to the lower plates thereof by reason of the fact that the two lowermost plates through which they extend in the upper group are also locked against movement by the bolts 23. All of the plates above the bottom plate 22 are locked together by a plurality of bolts 27 whose heads are seated in relatively deep recesses 28 provided in the lowermost plate 21 and whose shanks project upwardly into a longitudinal recess 29 provided in the under-side of the sow block 14. The anvil block is secured to the sub base 11 and to the main base 10 by means of anchor bolts 30 which extend upwardly through the bottom plate 22 and the intermediate plates 21 of the anvil block. All of these bolts and plates will be adjusted to meet the various requirements of the different applications.

The anvil block 13 may be assembled on the sub base 11 by first positioning the bottom plate 22 thereof on such sub base with the anchor bolts 30 projecting upwardly through the apertures provided therefor in such plate. The bolts 17, 23 and 27 may then be threaded through the aligned apertures provided therefor in the two plates 21 so that the heads of the bolts 17 are seated in the recesses 31 provided in the bottom surface of the lowermost plate 21 and the head of the bolt 27 is seated in the aperture 28 of such plate. Preferably a strong, short spring 32 is previously placed on the shank of bolt 27, adjacent to the head thereof, so that it will be positioned intermediate the head of the bolt 27 and the bottom of the recess 28, both the head of the bolt and spring 32 being entirely contained in such recess. The two plates 21, together with the bolts threaded therethrough may then be positioned on the bottom plate 22 so that the anchoring bolts 30 extend up through the aligned apertures provided in such plates therefor and the heads of the bolts 23 are seated in the recesses 24 of the plate 22. With the three plates 21 and 22 properly assembled, nuts are screwed on the threaded ends of the anchoring bolts 30 to secure such three plates of the anvil block securely to the main base 10 and the sub base 11. Two of the intermediate plates 20 may next be positioned on top of the plates 21 with the bolts 75

17, 23 and 27 properly threaded therethrough and the recesses 26 provided in one of such plates for the heads of bolts 25 in uppermost position. The five upper plates 20 may then be assembled together by threading therethrough the bolts 25 and then positioning such upper plates as a unit upon the stack of plates previously assembled so that the heads of the bolts 25 properly seat in the recesses 26. The top plate 19 is then laid on the uppermost plate 20 after the bolts 18 have been properly inserted therethrough so that the heads thereof seat in the recesses 33 provided in the undersides of such plate 19. The plates 19, 20 and 21 are then locked together by screwing nuts on the threaded ends of the two central bolts 27. After the footings of the super-structure of the hammer have been properly positioned on the projecting ends of the bolts 17 and 18, compression springs 35 are first inserted on the projecting ends of said bolts and then the footings are locked to the plates of the anvil block by screwing on the nuts 36.

It will be understood from the foregoing that the corrugations in the opposed faces of the plates which constitute the anvil block 13 lock such plates against movement relative to each other in one direction while the several bolts extending through such plates prevent movement or slippage of such plates relative to each other in a direction longitudinally of the corrugations. A number of the bolts also permanently lock and unite the several layers into a unitary mass and lock such unitary mass to the sub base 11 and main base 10 and to the super-structure of the hammer. It will be noted also that the construction and arrangement of the bolts and plates are such, that the parts of the bolts offer little resistance to subsequent deformation of such plates while in use and during such deformation are not subjected to forces which would tend to destroy them or render them useless for the purposes for which they were incorporated in the structure. The facility by which the layers may be assembled may be increased by welding groups of the plates together, for example, by welding the ends of the plates together so that they are secured by welded seams such as are indicated by the reference numeral 37 in Fig. 3 of the drawings. By so welding the ends of the plates, the whole anvil block may be assembled at its place of manufacture and then shipped as a unit to the place of installation where it can be immediately installed.

The plates 20, 21 and 22 are made from a tough, ductile steel or alloy, ferrous or non-ferrous, such as rolled, open hearth steel having a carbon content of from 0.10 to 0.90 or any other suitable grade of carbon or alloy steel possessing the necessary hardness and toughness and ductility for the purposes intended. Thus the plates are enabled to absorb relatively heavy shocks and stresses without failure and at the same time, due to the relative softness of the metal, are enabled under such stresses to become more firmly and permanently seated. For example, under the heavy impacts of the steam hammer, the metal of the plates will flow to the extent that the interlocking ridges and troughs of the plates will become more firmly seated and interlocked so that in time the metal plates under such impacts will be hammered into a homogeneous mass in which there will be no structural weaknesses and relatively little if any air spaces or separations as between the plates. A foundation of this character is practically indestructible and will

last for long periods. The plates may be case hardened or not heat treated depending upon the desired requirements and should preferably be as heavy and thick as is attainable for heavy machines and may be varied according to the requirements of each class of machines or applications where the bases are to be used. Also the plates may be of the same thickness if desired.

The top plate 19 may also be made of the same material as the plates 20, 21 and 22 but it may be preferable to make it of a heat treated alloy steel having greater hardness and toughness than the aforementioned rolled steel in order to obtain a better distribution over the entire area of the anvil block of the forces which will be exerted thereon through the sow block 14 during the operation of the hammer. By this more equal distribution of the load or stresses there is in time obtained also a more homogeneous uniting of the underlying layers of softer metal. Some of the steel alloys suitable for this purpose are chrome-molybdenum alloys, chrome-nickel alloys or vanadium steels as they possess the necessary hardness and toughness. The metal material of the top plate or plates 19 may be provided with a hard facing or surfacing to better accomplish the above results.

While I have illustrated in Figs. 1 to 3 of the drawings and above described a preferred embodiment of the invention, it will be apparent to those skilled in the art that changes and modifications may be made therein without departing from the spirit of the invention. Thus any number of plates 20 and 21 may be used and any suitable arrangement of the bolts may be made as is found to be desirable. In this latter connection the positions and arrangements of the bolts may be reversed or otherwise varied to suit the conditions of the particular application of the invention. The cushioning effect of the anvil block accomplished by the use of plates of a soft, ductile steel can also be enhanced by placing between the several layers of such block, thin sheets of material softer than that of which the plates are constituted, as for example, lead, bronze or wood. Shock absorbing sheets of this nature are indicated by the reference numeral 40 in Fig. 4 of the drawings. These sheets also have the added advantage that the material of which they are constituted will fill in any irregularities in the surfaces of the plate which may not be erased in the use of the block thereby obtaining a better seating of the plates relative to each other. By the use of welds 37 such as has been above described, such materials will be sealed in place for long periods or until they have been properly and permanently distributed between the steel plates. It will also be evident that instead of the corrugations heretofore described and illustrated, the surfaces of the plates may be otherwise formed or roughened in a predetermined manner so as to prevent slippage of the plates. For example, as is illustrated in Fig. 5 of the drawings, the plates may be formed so as to provide projecting members 41 which are constructed and arranged to interlock with correspondingly shaped depressions 42 provided in the opposed surfaces of the adjacent plates as is illustrated in Fig. 5 of the drawings. In such a construction the use of bolts or at least a large number of the bolts may be rendered unnecessary and discarded. Other changes may readily occur to those skilled in the art, hence I do not wish to limit myself to the preferred structure above described but in-

tend to include all structures coming within the scope of the appended claims.

I claim:

1. A foundation for supporting a machine comprising a concrete base, a unitary metal sub-base resting on said concrete base and being secured to the latter, a machine base mounted on said sub-base and secured to the latter and said concrete base, said machine base being of laminated construction and including a plurality of superimposed plates each having substantially the same surface area and composed of tough, ductile metal capable of absorbing heavy stresses without failure and under such stresses of enabling such plates to become more firmly united to one another, means securing said plates in superimposed relation and against slippage relative to each other so as to maintain such plates together as a unitary whole, and means for anchoring the machine upon the uppermost plate of said machine base, said last mentioned means including a plurality of metal members extending vertically through at least a plurality of said plates.

2. A foundation for a machine comprising a concrete base, a unitary metal sub-base resting on said concrete base and secured thereto, a unitary machine base mounted on said sub-base and secured to the latter and said concrete base, said machine base being of laminated construction and including a plurality of superimposed plates of substantially the same surface area and composed of tough, ductile metal capable of absorbing heavy stresses without failure and under such stresses of enabling such plates to become more firmly united to one another, the opposing surfaces of said plates being rough and the projections and depressions of such opposing surfaces being interengaged to secure said plates in superimposed relation and against slippage relative to each other in at least one direction, and means for anchoring the machine upon the uppermost plate of said machine base, said last mentioned means including a plurality of metal members extending vertically through at least a plurality of said plates.

3. A foundation for supporting a machine comprising a concrete base, a unitary metal sub-base resting on said concrete base and being secured to the latter, a machine base mounted on said sub-base and secured to the latter and said concrete base, said machine base being of laminated construction and including a plurality of superimposed plates of tough, ductile metal capable of absorbing heavy stresses without failure and under such stresses of becoming more firmly united to one another, the interior plates of said laminated machine base having a corrugated cross-sectional form so as to provide a plurality of alternately spaced ridges and troughs on the surfaces of such plates, the ridges and troughs on the surfaces of each plate being interengaged with the troughs and ridges, respectively, on the surfaces of adjacent plates, and means securing said plates against movement relative to each other in directions extending longitudinally of the troughs and ridges and anchoring the machine upon the uppermost plate of such machine base.

4. A foundation for supporting a machine comprising a concrete base, a unitary metal sub-base resting on said concrete base and being secured to the latter, a machine base mounted on said sub-base and secured to the latter and said concrete base, said machine base including a plu-

rality of superimposed plates forming a laminated structure and constituted of tough, ductile metal material, and means securing said plates in a superimposed relation and against slippage relative to each other, said securing means comprising a plurality of metal members extending vertically through a plurality of said plates and movable relative to at least some of the plates through which they extend under heavy stresses exerted on the laminated structure, and means associated with one end of each of said members to cushion

the strain on such member due to such heavy stresses.

5. A foundation such as defined in claim 4, in which each of said vertical members is secured at one end against substantial movement relative to one of said plates and is movable relative to the other plates through which it extends under the said stresses, and in which said cushioning means is in engagement with and coacts with the other end of said member.

LOUIS W. WILLIAMS.
